TRANSFORMER GASKET STRUCTURE

John A. McDonnell, Nahant, Mass., assignor to General Electric Company, a corporation of New York

Application December 30, 1952, Serial No. 328,729

2 Claims. (Cl. 174—52)

This invention relates to transformer gasket structures and more particularly to a new and improved gasket structure for a cover over an opening or recess in a transformer casing which is made of resilient rubber-like material.

Gaskets, in the form of cork or rubber-like rings, are often interposed between a rim or flange surrounding an opening or recess in a transformer casing and a cover for such opening in order to provide a tight seal when suitable cover fastening means is tightened so as to compress the gasket material. Sometimes the casing itself is made of resilient rubber-like material. For example, some electrical instrument transformers have their electromagnetic parts insulatingly embedded and resiliently supported in a molded butyl rubber casing which has a side recess for secondary winding terminals, which recess it is desirable to close tightly by means of a sealed but removable cover. One problem in connection with such a construction is that of removably attaching the cover tightly enough so that a gasket seal can be made. In accordance with this invention, a rigid backing member is located adjacent to the opening to be covered in the resilient casing material in such a manner that the portion of the resilient material surrounding the opening is clamped between the cover and the backing member and thus constitutes an integral built-in gasket.

An object of the invention is to provide a new and improved transformer gasket structure.

Another object of the invention is to provide a novel and simple integral built-in gasket structure for an opening or recess in a transformer casing which is made of resilient rubber-like material.

The invention will be better understood from the following description taken in connection with the accompanying drawing and its scope will be pointed out in the appended claims.

In the drawing Fig. 1 is a front elevation partly in section of an instrument current transformer embodying the invention, and Fig. 2 is a side elevation partly in section of the transformer shown in Fig. 1.

Referring now to the drawing, the transformer is indicated generally by the reference numeral 1. Its internal electrical and magnetic parts (not shown) may be of conventional construction and they are insulatingly embedded and resiliently supported in a molded casing 2 of resilient rubber-like material such as synthetic rubber of the butyl type. The entire structure is rigidly supported on a metal base plate 3 to which a pair of metal angle bar mounting brackets 4 are attached by bolts 5.

Extending from the top of the casing 2 are a pair of heavy current carrying high voltage terminals 6, the electrical insulating creepage distance of which to the normally grounded metal supporting parts 3 and 4 is increased by means of integral molded-on petticoats or flanges 7 in the casing material. In other words, the upper part of the casing material which is surrounded by the petticoat members 7 corresponds generally in function to a high voltage insulating bushing for the high voltage terminals 6. Set into a recess or cavity 8 in the front of the lower or main body portion of the casing 2 is a low voltage secondary winding terminal structure 9. The opening for the recess 8 is closed by a cover member 10.

2

Cooperating with the cover member 10 for the purpose of attaching the cover member firmly and removably in place and also making a tight seal between the cover member and the casing, there is provided a rigid backing member 11 preferably in the form of a metal ring or frame having an integral angularly extending bottom flange or foot 12 which may be attached to the main supporting plate 3 in a suitable manner such as by spot welding. When the housing or casing material is molded, it may surround the frame or backing member 11 so that the latter may also be embedded in the portion of the resilient casing material which surrounds the opening for the cavity 8. Thus, it will be seen that there is a portion 13 of the resilient rubber-like casing material which is between the backing plate 11 and the cover 10 and which constitutes an integral built-in gasket for the cover 10.

The cover may be fastened in place by any suitable means such as by the four thumb screws 14 which have been illustrated. As shown, these extend between the cover 10 and the backing plate 11 and pass through the suitable holes in the built-in integral gasket 13 so that when they are tightened, they will compress the built-in integral gasket 13 and thus form a tight seal.

While there has been shown and described a particular embodiment of the invention, it will be obvious to those skilled in the art that various changes and modifications may be made without departing from the spirit and scope of the invention and I, therefore, aim by the appended claims to cover all such changes and modifications as fall within the true spirit and scope of my invention.

What I claim as new and desire to secure by Letters Patent of the United States is:

1. In an instrument current transformer, a solid casing of resilient rubber-like material in which electromagnetic parts are insulatingly embedded and resiliently supported, a recess for secondary winding terminals in a side of said casing, a cover for said recess having a rim which corresponds in surface configuration to the part of the surface of said casing which surrounds the opening to said recess, a rigid backing ring embedded in said resilient rubber-like material under said part of the surface of said casing, said electro-magnetic parts and said backing ring being embedded in said casing during the molding thereof and threaded fastening means extending between said cover rim and backing ring for clamping therebetween a portion of said resilient rubber-like casing material so that said portion constitutes an integral built-in gasket which provides a water-tight seal for said cover.

2. In an instrument current transformer, a solid casing of resilient rubber-like material in which electromagnetic parts are insulatingly embedded and resiliently supported, a flat sheet metal base for said casing, a recess for secondary winding terminals in a side of said casing, a cover for said recess having a rim which corresponds in surface configuration to the part of the surface of said casing which surrounds the opening of said recess, a rigid backing ring embedded in said resilient rubber-like material under said part of the surface of said casing, said electro-magnetic parts and said backing ring being embedded in said casing during the molding thereof said backing ring having an integral angularly extending mounting foot attached to said sheet metal base, and threaded fastening means extending between said cover rim and backing ring for clamping therebetween a portion of said resilient rubber-like casing material so that said portion constitutes an integral built-in resilient gasket which provides a water-tight seal for said cover.
